CLAIM

The ornamental design for a skewed cube-shaped pillow foam filling as shown and described.

DESCRIPTION

FIG. 1 is a perspective view of a pillow and skewed cube-shaped pillow foam filling.

FIG. 2 is an enlarged perspective view a skewed cube-shaped pillow foam filling.

FIG. 3 is a front side view of the skewed cube-shaped pillow foam filling.

FIG. 4 is a top view of the skewed cube-shaped pillow foam filling.

FIG. 5 is a first side view of the skewed cube-shaped pillow foam filling.

FIG. 6 is a second side view of the skewed cube-shaped pillow foam filling.

FIG. 7 is a bottom view of the skewed cube-shaped pillow foam filling; and,

FIG. 8 is a back side view of the skewed cube-shaped pillow foam filling.

The broken lines in the drawings show environmental subject matter, and form no part of the claimed design. The dot-dash broken lines show areas of enlargement and form no part of the claimed design.

1 Claim, 3 Drawing Sheets
